UNITED STATES PATENT OFFICE

2,220,177

LOUD-SPEAKER

Arthur J. Sanial, Flushing, N. Y., assignor to Radio Corporation of America, a corporation of Delaware

Application March 31, 1938, Serial No. 199,323

4 Claims. (Cl. 181—27)

This invention relates to loud-speakers and, more particularly, to a horn structure therefor.

In certain installations of announce systems, it has been found desirable to prevent sounds within predetermined frequency ranges from reaching the diaphragm of the driving unit from the atmosphere. For example, in such installations on board battleships, the low frequency sounds produced by cannon fire have been known to travel back through the horn and to injure the diaphragm. It is the primary object of my present invention to provide an improved horn structure for loud-speakers wherein this danger is obviated.

More particularly, it is an object of my present invention to provide an improved horn structure for loud-speakers wherein sounds entering the horn from the atmosphere will be prevented from reaching the diaphragm.

Another object of my present invention is to provide an improved horn structure as aforesaid which is simple in construction and highly efficient in use.

In accordance with my present invention, I make the horn of two or more sections and fasten them together with one or more spacers of a given length. The spacers are so arranged as to provide an acoustic by-pass in the horn to prevent the low frequency sound that enters the mouth of the horn from reaching the diaphragm.

The novel features that I consider characteristic of my invention are set forth with particularity in the appended claims. The invention itself, however, both as to its organization and method of operation, together with additional objects and advantages thereof, will best be understood from the following description of several embodiments thereof, when read in connection with the accompanying drawing, in which

Figure 1 is a central sectional view of one form of horn embodying my invention,

Figure 2 is a front elevation thereof, and

Figure 3 is an elevation of a different form of spacing device from that shown in Figs. 1 and 2.

Referring more in detail to the drawing, wherein similar reference characters designate corresponding parts throughout, I have shown, in Figures 1 and 2, a loud-speaker comprising a suitable driving unit 1 which may include a conventional diaphragm (not shown) and to which is coupled a horn formed of two axially-aligned sections 3 and 5. The smaller section 3 is disposed immediately adjacent the driver 1, and the larger section 5 is spaced therefrom a predetermined distance in an axial direction, the adjacent

ends of the horn sections 3 and 5 being provided with radially outwardly extending, annular flanges 7 and 9, respectively. A plurality of spacers 11 of predetermined length are disposed circumferentially about the flanges 7 and 9 in spaced relation to each other and connect the two horn sections 3 and 5, the spaces 13 between the members 11 serving as acoustic passages for by-passing sound below substantially a predetermined frequency.

It will be seen that the spacers 11 connect the horn sections 3 and 5 into a unitary structure, and the internal contour of the united horn sections in a longitudinal direction is substantially smooth, that is, without any abrupt changes or interruptions, as clearly shown in Figure 1. The cut-off frequency of the horn assembly may, for example, be made at about 200 or 250 cycles, and this will determine the length of the spacing members 11 and the distance which they are spaced from each other circumferentially of the horn.

In place of a plurality of spacing members 11, the horn sections 3 and 5 may be connected by a ring-like or annular member 21, as shown in Fig. 3. The member 21 is provided with a plurality of radially extending passages 23 spaced circumferentially about the ring member 21 and corresponding to the acoustic passages 13.

Although I have shown and described two modifications of my invention, it will be apparent to those skilled in the art that many other modifications are possible. I, therefore, desire that my invention shall not be limited except insofar as is made necessary by the prior art and by the spirit of the appended claims.

I claim as my invention:

1. A loud-speaker horn comprising a plurality of horn sections, and spacing means spaced circumferentially about said horn sections connecting said horn sections into a unitary structure, said spacing means providing a plurality of radially extending, circumferentially spaced passages constituting an acoustic by-pass for sounds below substantially a predetermined frequency.

2. A loud-speaker horn comprising a pair of horn sections arranged in axial alignment and in spaced relation to each other in an axial direction, and spacing means connecting said sections to each other in said spaced relation, said means having a plurality of circumferentially spaced acoustic passages for by-passing sound below substantially a predetermined frequency.

3. A loud-speaker horn comprising a pair of horn sections arranged in axial alignment and in

spaced relation to each other in an axial direction, the adjacent ends of said horns having outwardly extending flanges thereon, and spacing means between said flanges connecting said horns into a unitary structure and maintaining said horn sections in spaced relation, said means providing a plurality of circumferentially spaced acoustic passages for by-passing sounds below substantially a predetermined frequency.

4. The invention set forth in claim 3 characterized in that said connecting means comprises an annular member having a plurality of circumferentially spaced, radially extending passages therein.

ARTHUR J. SANIAL.
